UNITED STATES PATENT OFFICE

152,291

DESIGN FOR A LAMP

Herman Rubin, Los Angeles, Calif., assignor to National Pictorial Lamp, Inc., Los Angeles,
Calif., a corporation of California

Application July 28, 1947, Serial No. 140,565

Term of patent 14 years

(Cl. D48—20)

To all whom it may concern:

I, Herman Rubin, a citizen of the United States, residing at Los Angeles, in the county of Los Angeles, State of California, have invented a new, original, and ornamental Design for Lamp, of which the following is a specification, reference being had to the accompanying drawing, forming a part thereof.

With regard to the figures, the side of the lamp opposite from the side shown is substantially similar in appearance.

I claim:

The ornamental design for a lamp, as shown and described.

HERMAN RUBIN.
